UNITED STATES PATENT OFFICE.

JOHN RASP, OF MCKEESPORT, PENNSYLVANIA.

MULTIPLE-ROD BRACKET.

Application filed March 31, 1928. Serial No. 266,330.

This invention relates to combined curtain rod and shade roller brackets and more particularly to a device of this character adapted to simultaneously support a plurality of curtain rods.

An important object of the invention is to provide a novel and improved support for the present day extensible curtain rods which is of such character that the curtain rod will be 10 very firmly held in position and the curtain applied thereto may be extended beyond the actual end of the rod so that it hides the fixture from view.

A further object of the invention is to provide a device of this character which, while equipped to support a given number of rods, may be employed to support a lesser number of rods and in which detachable elements are provided for engaging the rods which may be 20 removed when not in use.

A further object of the invention is to provide a device which will enable straight rods to be employed and will give to these rods a bowed end appearance which materially enhances the beauty of the fixture and of the curtain applied thereto.

A still further object of the invention is to provide a device of this character which may be readily and cheaply manufactured, which 30 will be durable and efficient in service and a general improvement in the art.

These and other objects I attain by the construction shown in the accompanying drawing, wherein for the purpose of illustration is 35 shown a preferred embodiment of my invention and wherein:—

Figure 1 is a perspective view of a bracket as viewed from the rear, a curtain rod being indicated in position upon one of the rod 40 holders in dotted lines;

Figure 2 is a vertical sectional view on the line 2—2 of Figure 1;

Figure 3 is a section on the line 3—3 of Figure 2.

Referring now more particularly to the drawings, the numeral 10 designates a metallic strip vertically ribbed at 11 to reinforce the same. The upper end of this strip is provided with a perpendicularly disposed flange 12 adapted to seat upon the upper end of a window frame against the face of which the strip 10 is disposed and having tangs 13 to enter this frame. The lower end of the strip preferably has projecting outwardly therefrom a shade roller bracket 14. At one side edge, the strip is provided with horizontal

arms 15 which have their upper and lower edges reverted, as at 16, to provide opposed channels 17, each adapted to receive one end of a curtain rod holder 18.

60

As is well known to those familiar with the art, the present day flat type curtain rod is in the form of a sheet metal strip 19, the side edges of which are reverted, as at 20, to produce opposed channels. The rod holders each 65 comprise a substantially U-shaped strip of spring metal, the end of one arm 20 of which is slightly angularly deflected, as at 21, and is of a size to enter and fit between the bases of the channels produced by the reverting of 70 the edges of the curtain rod.

The deflection at 21 effectually limits the extent to which the rod may be forced thereon. The opposite arm 22 is adapted to enter and fit between the bases of the channels 17 75 of the arms of the bracket and these arms are preferably offset at the point of their connection to the bracket, as indicated at 23, so that they form an end wall, limiting the extent to which the arms 22 may be inserted 80 therein and placing the inner faces of the reverted portions in the same plane as the rear face of the strip 10.

It will be obvious that such brackets must be made in pairs and that the arms thereof 85 will project from the outside faces, so that the bowed rod supports project beyond the outer edges of the brackets and the bracket may be effectually concealed by passing the curtain about the supports.

90

As the construction employed is obviously capable of a certain range of change and modification without materially departing from the spirit of the invention, I do not limit myself to such specific structure except as 95 hereinafter claimed.

I claim:—

1. A curtain rod holder comprising a bracket having means whereby it may be secured to a support, a plurality of flat arms 100 projecting from the outer side edge of the bracket and having the edges thereof reverted to provide opposed channels and U-shaped metallic strips each having one arm thereof adapted to enter and support an end of a 105 curtain rod and the opposite arm thereof adapted to engage between the channels of the arm and fit therebetween.

2. A curtain rod holder comprising a bracket having means whereby it may be 110 secured to a support, a plurality of flat arms projecting from the outer side edge of the

bracket and having the edges thereof reverted to provide opposed channels and U-shaped metallic strips each having one arm thereof adapted to enter and support an end 5 of a curtain rod and the opposite arm thereof adapted to engage between the channels of the arm and fit therebetween, the reverted edges of the arms being at the rear faces of the arms, the arms being offset forwardly to

place the rear faces of the reverted portions 10 in the same plane as the back of the strip and produce end walls limiting movement of the last named arms with relation to said channels.

In testimony whereof I hereunto affix my 15 signature.

JOHN RASP.
